LATHER-APPLYING SAFETY RAZORS

Edward R. Boland, Boston, Mass.

Application September 20, 1955, Serial No. 535,382

2 Claims. (Cl. 30—41)

This invention relates to improvements in lathering safety razors. More particularly the invention provides improved lathering means on or attachable to a safety razor for effecting more efficient application and utilization of shaving cream as compared with prior lathering proposals. The invention operates on a cream-conserving principle whereby a relatively small amount of shaving cream, or the like, initially deposited on the lathering means, is repeatedly collected and re-applied to the skin throughout any shaving process, with said initial deposit of cream serving the lathering requirements of the entire shaving process.

It is among the objects of the invention to provide a razor and lathering combination wherein roller means operates within a collector chamber adjacent to a shaving edge of the razor with the roller means positioned for contacting the skin in advance of the shaving edge in the shaving process and with the collector chamber arranged and adapted to collect lather and moisture scraped from the skin in the shaving process, the lather and moisture mixing in the collector chamber to maintain a collected supply of lather of proper consistency for effective repeated re-applications by the roller means to the skin as the shaving process proceeds.

Another object of the invention is to provide a razor and lathering combination wherein a sectional roller has its sections individually rotatable on a common axis within a lather-collecting chamber located adjacent to and in advance of a shaving edge of the razor, whereby said collector chamber collects lather scraped from the skin in the shaving process, and said sectional roller, or one or more sections thereof, engages and rolls over the skin to repeatedly re-apply lather from the collector chamber to the skin as the shaving process proceeds.

A further object of the invention is to provide a lathering attachment for safety razors which readily and quickly may be mounted in operative relation to a shaving edge of a conventional safety razor for collecting lather scraped from the skin in the shaving process and for repeatedly re-applying the collected lather to the skin as the shaving process proceeds.

It is, moreover, my purpose and object generally to improve the structure and efficiency of safety razors having lathering means associated with a shaving edge thereof, and especially such razors wherein roller means operates within a lather collecting chamber for repeatedly re-applying collected lather to the skin in a shaving process.

In the accompanying drawings:

Fig. 1 is an edge elevational view of a lathering safety razor embodying features of the invention and showing the general disposition of the razor in service;

Fig. 2 is a side elevation of the razor of Fig. 1 looking at that side having the lathering means;

Fig. 3 is a cross-sectional view on line 3—3 of Fig. 2, on a larger scale;

Fig. 4 is a perspective view of the lathering unit of Figs. 1—3, separated from the razor;

Fig. 5 is an elevational view showing a slightly modified form of lathering unit clipped to a conventional single edge type of safety razor;

2

Fig. 6 is a front elevation of the lathering unit of Fig. 5, per se;

Fig. 7 is a view generally similar to Fig. 5 but showing another slightly modified form of lathering unit 5 clipped to a different conventional style of single edge razor;

Fig. 8 is a front elevation of the lathering unit of Fig. 7, per se;

Fig. 9 is a view generally similar to Figs. 5 and 7 but showing still another modification of the lathering unit mounted on a third variety of conventional single edge razor; and

Fig. 10 is a top plan view of the lathering unit of Fig. 9, per se.

15 Referring to the drawings, the invention is represented in Figs. 1—3 associated with one conventional double-edge variety of safety razor having a head indicated generally at 10 on one end of the handle 12.

According to the invention, a collecting trough or 20 chamber indicated generally at 14 has roller means 16 mounted therein with a substantial portion of the roller means exposed. The roller means 16 and the trough or chamber 14 may be mounted on the razor by any suitable means with the roller means disposed in spaced 25 relation to and in advance of one shaving edge portion of the head 10, in position to engage and roll over the skin during a shaving process. The trough or chamber 14 is adapted and positioned to collect lather as it is scraped from the skin in the shaving process, and the 30 collected lather is repeatedly re-applied to the skin by the roller means 16 as the shaving process proceeds.

In Figs. 1—4, the roller means 16 and the trough or chamber 14 are represented as a unit designed to be 35 removably attached to the razor handle 12 by means of

the resilient clip 18. The trough or chamber 14 is defined by the generally right-angularly related walls 20, 22, and the end walls 24, 26 which support a rod or shaft 28 on which the roller means 16 may be rotatably mounted. The roller means may be a single relatively

40 long roller if desired but, preferably, will consist of a plurality or series of roller sections 16' of which four sections are represented in Figs. 2 and 4. Desirably, each roll section will be of a suitable resiliently soft material, such as gum rubber, or a synthetic or plastic material having resilient softness comparable to gum rubber. Each roller section has a separate bearing bushing 45 17 on the shaft or rod 28, and the bushings and roll sections should have a suitable amount of looseness and play to ensure against binding or sticking of the roller sections in use.

The trough or chamber wall 20 has substantial length and, after the unit has been clipped on the razor handle 12, the free end of this wall 20 may be thrust into engagement with a wall of the razor head, as best seen in 55 Fig. 3, by sliding the unit along the handle 12. This brings the trough and roller means into proper operative relation to a shaving edge portion of the razor head 10.

It is a feature of the invention that only a relatively 60 small initial deposit C of shaving cream, or the like, deposited along the roller means 16 may serve for an entire shave, thereby to effect a substantial saving in shaving cream. Perhaps more important, however, is the fact that a more efficient and satisfactory shave may be had using the unit of the invention, as compared with prior practices and devices, without the trouble and messiness of applying lather to the skin preliminarily to shaving. The invention makes this pre-lathering unnecessary. The face, or other part to be shaved, desirably should be washed with soap and water, followed by rinsing. With the skin left relatively moist, the shaving process may begin. Assuming that a deposit C of cream has been placed along the roller means 16, the 65

shaving process may proceed in the usual way with the roller means 16 engaging and applying cream to the skin in advance of the shaving edge, as illustrated in Fig. 1, and with the trough or chamber 14 in position to collect the lather as it is scraped from the skin in the shaving process.

Inasmuch as the skin preferably will be in a moistened condition, an appreciable amount of moisture is scraped from the skin along with the cream or lather with the result that the lather which is being collected in trough or chamber 14 constantly is maintained in a condition to be effectively picked up by the roller means 16 for re-application to the skin over and over as the shaving process proceeds. The moisture which constantly is being scraped from the moist skin and added to the lather in the trough or chamber 14 maintains an efficient consistency of the collected and re-applied lather. The lather tends to flow as it is scraped from the skin so that it readily enters the collector trough or chamber 14, under the urge of roller means 16, rather than clinging to and tending to clog the shaving edge portion of the razor. Also, this constant adding of moisture to the collected lather conditions the lather for easy and efficient cleaning of the razor and lathering unit by inserting the assemblage into a stream of water, preferably after sliding the lathering unit along the handle 12 away from razor head 10.

The lathering means desirably will be of non-corrosive materials and, when the means is in the form of a unit attachable to and removable from conventional varieties of safety razors, as herein shown, the lathering unit may have size and contours for being accommodated within any particular conventional variety of safety razor case.

It will be apparent that the herein described lathering means or unit does not interfere with opening and closing of the razor head for insertion and removal of blades, and does not interfere with customary manipulations of the razor in any shaving process, excepting that shaving of the upper lip should be accomplished by cross-strokes of the razor rather than by up and down strokes, inasmuch as it is not feasible to operate the roller-applicator over the upper lip and under the nose unless the motion is transversely of the face.

Also, it should be noted that the disposition of the roller means along the shaving edge, in predetermined spaced relation thereto, tends to stabilize shaving strokes of the razor thereby minimizing the likelihood of cutting or knicking the skin in the process of shaving.

Referring more particularly to Figs. 5-10, the lathering unit of the Figs. 1-4 embodiment requires but slight modification to adapt it for operative association with any of the conventional single edge varieties of safety razors.

Figs. 5 and 6 show a modified form of lathering unit clipped (in Fig. 5) to one conventional style of single edge safety razor, the unit being generally the same as that of the Figs. 1-4 form with a slightly different relationship of the attaching clip 18^a, and with the free end portion of the trough or chamber wall 20 shaped at 21 to enter a frame opening which is present in the head of the razor of Fig. 5. The end walls 24^a, 26^a of the Figs. 5 and 6 unit extend closer to the free edge of wall 20 as compared with the Figs. 1-4 embodiment. Also, an extension part 20^a on the lathering unit of Figs. 5 and 6 projects a substantial distance beyond wall 22 in direction away from the razor head, and clip 18^a, which may be similar to clip 18, is mounted at the free end portion of extension part 20^a in position to resiliently grip the handle of the razor shown in Fig. 5.

Figs. 7 and 8 show another slightly modified form of lathering unit clipped (in Fig. 7) on the handle of a second variety of conventional single edge razor. Here again, the modifications, as compared with the Figs. 1-4 unit, are in the relationship of the clip to the trough or

chamber and in the notching of the free end of the wall 20, as at 21', for entering spaced slots in a frame part of the head of the razor shown in Fig. 7. In this case, the clip 18^a is secured to the unit wall 20 behind the sections 16' of the roller means 16, in position to resiliently engage around handle portions of the razor of Fig. 7.

The single edge variety of razor as shown in Figs. 9 and 10 has a centrally disposed generally U-shaped member 30 thereon to which the illustrated lathering unit conveniently may be clipped by a clip 32 on wall 20 which may engage back of member 30 when the lathering unit is forced away from the eye in Fig. 9 in the direction of the axis of the roll means 16 to its operative position of Fig. 9. The free end of wall 20 is shaped generally the same as in the Figs. 5 and 6 embodiment. Clip 32 is of the well known pocket clip variety secured at one end to unit wall 20, as at 33, and having its resilient body portion in spaced general parallelism with wall 20, so that member 30 can enter between wall 20 and said resilient body portion of the clip.

Each of the lathering units of the Figs. 5-10 embodiments, when removed from their respective razors, are suitable for arrangement in available space within the conventional cases for the illustrated razors.

Although the shaving cream C initially applied to the roller-applicator may be of any variety capable of providing a suitable lather on the skin, it is desirable and recommended that one of the so-called brushless varieties of shaving cream be employed for best results.

It is intended that the patent shall cover, by suitable expression in the appended claims, whatever features of patentable novelty exist in the invention disclosed.

I claim as my invention:

1. In a safety razor having a head portion for holding a razor blade and a handle on which said head portion is mounted, a lather-collecting receptacle having one side open toward said head, said receptacle removably mounted on said handle and movable along said handle in directions toward and from said head portion, roller means rotatably mounted in said receptacle at the open side thereof, said receptacle having a wall portion for engaging said head portion of the razor when the receptacle is moved toward said head portion thereby to stop the receptacle with its open side in a position to receive lather scraped from the skin by the razor blade in a shaving process, said roller means constituting a lather applicator for rolling over the skin in advance of the shaving edge of the razor blade in said shaving process and for picking up lather collected in said receptacle and re-applying it repeatedly to the skin as said shaving process proceeds.

2. A lathering attachment for safety razors, comprising a generally trough-shaped receptacle having a bottom wall, a side wall and two end walls, and having one side open roller means rotatably mounted within said receptacle with a surface portion exposed at said open side thereof, said roller means having bearings in said end walls, and clip means on one of said walls for removably mounting said receptacle on a safety razor with the said open side of the receptacle in lather-collecting relation to the shaving edge of the blade of the razor and with said roller means in spaced lather-applying relation to said shaving edge of the razor blade.
